Term of patent 14 years

Int. Cl. D11—02; D26—01

U.S. Cl. D48—2

FIG. 1 is an elevational view of a candleholder showing my new design;

FIG. 2 is a top view of the design of FIG. 1;

FIG. 3 is a bottom view of the design of FIG. 1; and

FIG. 4 is a view of a portion of the surface pattern which is uniformly continuous around the candleholder, it being understood that the candleholder would appear in normal side elevation as shown in FIG. 1.

I claim:

The ornamental design for a candleholder, substantially as shown and described.
